UNITED STATES PATENT OFFICE.

JOACHIM BOLLIGER, OF MONROE, WISCONSIN.

SAW-CLAMP.

1,288,817.

Specification of Letters Patent. Patented Dec. 24, 1918.

Application filed February 9, 1918. Serial No. 216,276.

To all whom it may concern:

Be it known that I, JOACHIM BOLLIGER, a citizen of the United States, residing at Monroe, in the county of Green and State of Wisconsin, have invented new and useful Improvements in Saw-Clamps, of which the following is a specification.

This invention comprehends the provision of a saw clamp designed to permit the component parts thereof to be quickly disassembled for a convenient arrangement of the clamp in a tool chest or the like, the invention residing in the construction, combination and arrangement of parts as claimed.

15 In the drawing forming a part of this specification like numerals of reference indicate similar parts in the several views, wherein—

Figure 1 is a side elevation of a clamp 20 constructed in accordance with my invention;

Fig. 2 is a perspective view of one of the pivoted members thereof;

Fig. 3 is a transverse sectional view taken 25 on line 3—3 of Fig. 1;

Fig. 4 is a similar view taken on line 4—4 of Fig. 1;

Fig. 5 is a similar view taken on line 5—5 of Fig. 1.

30 The clamp constructed in accordance with my invention consists of a pair of identically constructed members 10, each formed with apertured lugs 11 disposed in overlapping relation and through which a bolt 12 is 35 passed constituting a pivot about which members may be moved singly or in unison. While the members 10 may be constructed from any suitable material and configuration, they are preferably formed from metal 40 and are given a substantially U-shaped formation. Projecting from the parallel portion of one of the members 10 is a block 13 disposed adjacent the end of said member, and this block is riveted or otherwise suitably secured to the member. A block 14 is 45 arranged in a similar manner and secured to the member 10 and at an appropriate point above the pivot thereof. Projecting from the block 13 is a plate 15 formed at its outer 50 extremity to provide an interiorly threaded sleeve 16 to accommodate an adjusting screw 17. The screw has a swivel connection as at 18 with a relatively broad member 19 which is adapted to engage the bench or other support shown in dotted lines to which the 55 clamp is attached. Projecting from the

member 19 is a pointed spur 20 which is embedded in the bench or other support when the member 19 is brought into contact therewith as will be readily understood. Projecting from the block 14 in the same direction of the plate 15 is a pair of spaced wings 21 which are disposed above the plate 15 and lying in a plane at the opposite sides of the latter, and coöperating with the screw 17 and the member 19 to maintain the clamp fixed relatively upon a bench or other suitable support. The wings are divergently disposed as shown to space the forward extremities thereof the requisite distance to obtain an effective purchase upon the bench or other suitable support with which the clamp is used. In the further accomplishment of this end the forward extremity of the wings are curved downwardly to provide the 75 pointed spurs as 22 which embed themselves in the bench or other support as will be readily understood. In practice, the edge of a bench, shelf or other suitable support is positioned between the plate 15 and wings 21, 80 subsequent to which arrangement the screw 17 is adjusted to bring the member 19 into engagement with said support thereby clamping the latter between the member 19 and the wings 21. When thus positioned 85 upon the bench or support the member 10 carrying the attaching means is held stationary, while the other of said members 10 may be moved upon its pivot into gripping relation with the stationary members. After the 90 saw to be treated is placed between the members 10, and the movable member moved into gripping relation with the stationary member the thumb screw 23 carried by the movable member is brought into engagement 95 with the fixed member 10 for the purpose of holding said members in gripping relation. A block 24 is positioned between the parallel portion of the movable member and riveted or otherwise suitably secured thereto, the 100 block having a threaded bore through which the screw 23 passes.

Associated with each of the members 10 is a substantially V-shaped jaw the shank of which is indicated at 25 to fit endwise 105 between the parallel portion of the members while the cross pieces 26 of the respective jaws are disposed in confronting relation as shown. The cross pieces 26 rest upon the upper extremities of the members 10 110 and have their adjacent faces extended a slight distance beneath the ends of the mem-

bers 10 to provide relatively broad surfaces 27 between which the saw is effectively clamped. The shank 25 of each jaw is provided with a pair of spaced openings 28 which are adapted to register with similar openings in the parallel portions of the respective members 10 for the reception of a headed bolt 29. This bolt and the pivot bolt 12 are identical in construction, each 10 being bifurcated at its forward extremity and having a locking element 30 pivoted between the separated portion defined by the bifurcation. When the bolts are passed through their associated parts, the locking 15 element is swung upon its pivot to lie in a plane with the bolt, but subsequent to the proper positioning of the bolt the locking element is swung upon its pivot to lie transversely to the longitudinal center of the 20 bolt to prevent the casual separation of its associated parts. Coil springs 31 encircle the bolts adjacent the head portion thereof, and when the bolt is placed in position the spring is placed under tension operating 25 to hold the locking element 30 effectively engaged beneath the adjacent side of the member through which it is passed, to prevent loss of the bolt as will be readily understood. Manifestly by reason of this construction the gripping jaws may be separated from the members 10 by simply extracting the bolt 29, and the members 10 in turn separated by extracting the pivot bolt 12. This disassemblage of the parts is desirous to permit the clamp to be conveniently arranged in a tool chest or the like, and occupy a minimum amount of space therein. In addition to the device being extremely simple in its construction, it possesses maximum strength and may be conveniently handled for the purpose intended.

While it is believed that from the foregoing description, the nature and advan-

tages of the invention will be readily apparent, I desire to have it understood that what is herein shown and described is merely illustrative of the preferred embodiment of the invention, and that such changes may be resorted to when desired as fall within the scope of what is claimed. 50

What I claim is:—

1. In a clamp of the character described, a pair of pivoted members, means for holding said members in a given position, each of said members being of substantially U-shaped formation in cross section, clamping jaws carried by the members, and each jaw having a shank slidably fitted between the parallel portions of said members, said shanks and parallel portions having aligned openings, bolts passed through said openings, a locking element pivotally associated with each bolt and adapted to be arranged at right angles thereto, and a spring encircling said bolt and arranged to exert pressure in a direction to hold the locking element in effective engagement with the adjacent side of said member with which it is associated. 55

2. In a clamp of the character described, a pair of pivotally connected members, clamping jaws carried by the respective members, means for holding said members fixed in a given position, a block projecting laterally from one of said members, a pair of divergently disposed wings projecting from said members at a point above said block, said wings terminating in planes at the opposite sides of the block, an adjusting screw carried by said block, and means carried by said screw and coöperating with said wings for clamping the device upon a fixed support. 70 75

In testimony whereof I, affix my signature.

JOACHIM BOLLIGER.
